LAMINATING MACHINE

Robert H. Crowle, Berwyn, and Charles E. Jones, Evans-
ton, Ill., assignors to American Photocopy Equipment
Company, Evanston, Ill., a corporation of Illinois

Application September 17, 1958, Serial No. 52,662

Term of patent 14 years

(Cl. D66—1)

Figure 1 is a front perspective view of a laminating machine, embodying our new design, with the work table lowered.

Figure 2 is a front perspective view with the work table raised.

Figure 3 is a rear perspective view.

Figure 4 is a side view taken from the right of Fig. 1. We claim:

The ornamental design for a laminating machine, as shown.
